Samuel Lynde, Jr., Needham, Mass.
Setters Patent

The schedule referred to in these Letters Patent and making part of the same, containing a description in the words of the said Samuel Lynde Jr. of his improvement in the mode of planing & shaping huts."

It all to whom these presents shall come,
— Be it known, that Samuel Lynde Jr. of the town in the
county of Norfolk Commonwealth of Massachusetts has invent-
ed a new and useful improvement in the mode of planing and
shaping huts, & that the following is a full & exact description of the same,
and of the operation of the machinery therefor, as invented by me.

The said hut is the dwelling house or house or other building of
a hut composed of copper or other suitable metal, set in such a
fashion as to stand upright, said hut should be about two feet
in width, one foot in height, and of any convenient length, from
two feet or more, a wooden frame or box is placed across the hut
of the same width & length, so that it is only an excess of the height
of the hut, making it stand about two feet high, & having a
about five inches diameter is placed longitudinally over the
box or hut, the judgment of which rest upon the ends of said frame
box or hut, so the frame, this frame or box is placed at each end
and thereby held by C. between the cylinder and the sides of the frame
box there is a space of about 1/2 an inch or fine crevices, and by this
crevices of a garment cloth is laid; and the middle of the cloth
being raised or fastened to the upper side of the cylinder, &c. the
two ends of the garment represented by garment is drawn into the
cylinder and are then raised above the sides and are either to
wound round the cylinder, when it is desired that the garment
shall descend far down into the hut, the sides may be raised

from the bottom. When it is desired to let it fall a long distance into the water, the ends of the apron may again be rolled up round it. This apron is then covered at the bottom with bat bodies, if for planking two orthic layers high; if for napping then only two layers deep. The cylinder is put in motion by a crank motion or in any other way. It requires a cog-wheel or pinion by which the cylinder is turned. The point of the circumference at C describes until it has performed nearly half a revolution; it is then arrested, carried back and over on the other side until it makes nearly half a revolution on that side, and is then arrested and carried back and down again as before. As the cylinder moves the lower point in the apron necessarily descends on one side and rises on the other. Whether the apron is rising or descending, the bat bodies, which lie in its bed or trough, receive a lateral motion. At the apron sides, they roll in one direction; as it descends they roll in the contrary direction.

In planking the bottom, the apron should move only in straight lines for that purpose the cords may be taken by hand. The bottom &c. being there the apron should descend into the water. The hand should be prepared for napping as that, if they were to be napped in the ordinary way, g.g. represents the water line. The bottom may contain more or less water according to circumstances. It must be kept over the whole man should prevent the steam from getting. It is obvious that a little of different dimensions may be constructed.

If the diameter of the cylinder is greater, the bottom should be wider. The same steady and alternating motion in rolling & this shifting from forwards to backwards may be given to bat bodies, by placing those in the inside of a cylinder and then giving the cylinder the alternating or shifting motion above described. To which end the cylinder should allow of the admission of air and water. It is evident that when the apron is going up, the water will receive an

as my invention or improvement in planking and nailing
hat-bodies & for which I have a claim lettered Dated 11. the
giving a rotary & oscillating motion, i.e. rotary & then
shifting from forwards to backwards, to hat-bodies placed
in the bed or trough of a wagon or in side of a culverine as
above described.
